UNITED STATES PATENT OFFICE.

FREDERICK CHARLES SEYMOUR, OF CHICAGO, ILLINOIS, ASSIGNOR TO JOSEPH HALSTED CO., OF CHICAGO, ILLINOIS, A CORPORATION OF ILLINOIS.

COUNTERBALANCED STAIR.

1,015,645.

Specification of Letters Patent. Patented Jan. 23, 1912.

Application filed May 17, 1911. Serial No. 627,745.

To all whom it may concern:

Be it known that I, FREDERICK CHARLES SEYMOUR, a citizen of the United States, residing at Chicago, in the county of Cook and State of Illinois, have invented certain new and useful Improvements in Counterbalanced Stairs, of which the following is a description.

My invention belongs to that general 10 class of devices generally employed to complete a fire escape from the point where the ladder terminates some distance above the ground, and to temporarily extend the same to the ground when occasion may require. 15 When not so employed it is designed to be positioned in a horizontal plane near the line of the pivot, carrying the same so as not to obstruct the place below the fire escape, or provide means for prowlers to 20 gain access to the building.

My invention has among its objects the production of a simple, efficient, effective and economical construction of the kind described for use wherever found applicable.

To this end my invention consists in the 25 novel construction, arrangement and combination of parts herein shown and described, and more particularly pointed out in the claims.

In the drawings, wherein like reference 30 characters indicate like or corresponding parts, Figure 1 is a side elevation of my device lowered into operative position. Fig. 2 is a plan view of the same. Fig. 3 is a 35 sectional view taken substantially on line 3, 3 of Fig. 1. Fig. 4 is a view of the upper end of the ladder looking outward from the building to more clearly show the construction. Fig. 5 is a sectional view through the 40 pivotal support and adjacent parts. Fig. 6 is a sectional view taken substantially on line 6, 6 of Fig. 2. Fig. 7 is a sectional view similar to a portion of Fig. 5, of a modified construction. Fig. 8 is a sectional view 45 taken substantially on line 8, 8 of Fig. 7.

In the preferred form shown in the drawings, 1 is the outer side bar of the ladder, and 2 is the inner side bar, provided with steps 3, 3 arranged therebetween in the 50 usual manner. The pivot rod 4 may be supported upon the side of the building in any usual or preferred manner, as shown, it is supported by the hangers 5, 5, extending from a suitable boom, or its equivalent (not 55 shown). Loosely mounted on the pivot bar

4 is a tubular part 6, the ends only of the part 6 resting upon the pivot. The ends of the part 6 are flanged, as shown at 7, and have secured thereto plates 8, to the upper end of which are secured the side bars 1, 2, 60 and thus arranged, said side bars and the ladder are supported a distance above the pivotal center, as shown.

Upon the outer side bar 1 of the ladder, and firmly secured to the plate 8, I arrange 65 a suitable angle bar or post 9, and along the side of the bar 1, other posts 10, which carry truss rods 11, the upper one of which extends downward and is secured near the free end of the side bar. The said rod 70 serves also as a hand rail. Upon the inner side I also prefer to construct the ladder in substantially the same way, the angle irons or posts 12 and rods 13 serving a similar purpose. 75

Carried upon the outer side bar 1, as shown, from the post 9, and a portion of the posts 10, 10, by struts or angles 14, 14, etc., I arrange the counterweight bar 15, upon the free end of which is secured the counter- 80 weight 16. The counterweight is preferably adjustably secured upon the bar so that it may be positioned as desired to secure the most satisfactory results. As shown in the drawings, I preferably extend the upper 85 rod 11 to the counterweight and secure the same thereto, a turn-buckle or equivalent means being provided for affording adjustment. If desired, additional supporting rods 18 and 19 may be provided, the same being 90 suitably secured to the posts 9 and 12 carried by the side bars, and to the side bars.

A slightly modified construction for the integrally formed tubular part 6 and flanges 7 is shown in Figs. 7 and 8, in which 4 and 95 5 represent the pivot rod and one of the supports. Arranged on the pivot 4 is a tubular member 21, which is preferably squared at each end and provided with a part 23, arranged to be fitted thereon, 100 which part is provided with a flange 22. The part 20, which is similar to the part 8 in the other construction, is secured to the flange 22 by screws, bolts, or their equivalents for the purpose. The parts 23 may be 105 prevented from slipping off of the tubular part 21 by set screws 24, or their equivalents. The end of the tubular part being squared or irregular, there is no strain on the set screws 24 except to maintain the 110

parts together. This construction is the equivalent of the construction illustrated in Fig. 5, but somewhat more economical in manufacture.

5 The ladder is preferably constructed with the center of gravity above and proximate the pivotal support, so that when the ladder is operated, the center of gravity is shifted from side to side; that is to say, when the 10 ladder is in longitudinal position, the center of gravity is to that side of the pivotal support upon which the counterweight is located, and tends to hold the ladder in horizontal position, but when the ladder is 15 depressed in operative position, the center of gravity is moved past the vertical plane of the pivotal support so that the ladder is maintained down.

It will be seen from this brief description 20 that the whole device constitutes a compact and comparatively rigid ladder, the free end of the inner side bar 2 being sustained against sagging or dropping, by means of the connecting sleeve or tube 6, or its equivalent 25 in the tubular part 21, to which each of the side parts are secured, and by the cooperating truss posts and rods mentioned; that is to say the torsional strength of said sleeve together with the truss rods is sufficient to 30 support the free end of the inner side bar and prevent its sagging, thereby obviating warping or twisting of the ladder.

Having thus described my invention, it is obvious that immaterial modifications may 35 be made without departing from the spirit of my invention, hence I do not wish to be understood as limiting myself to the exact form, arrangement or combination of parts herein shown and described, or uses mentioned.

What I claim as new and desire to secure by Letters Patent is:

1. A counterbalanced stair, comprising suitable side bars, with steps arranged therebetween, means loosely engaging the side bars for pivotally supporting the stair, a rigid tubular member rigidly connecting the side bars adjacent their connection with the means for pivotally supporting the stair, a 50 counterbalance bar arranged upon one of the side bars of the stair, and a counterweight positioned on said counterbalanced bar.

2. A counterbalanced stair comprising suitable side bars with steps arranged therebetween, means for supporting said stair comprising a pivot rod loosely engaging the side bars of the stairs, a rigid tubular brace rigidly connected to the side bars of the stairs and surrounding said pivot bar, a 55 counterbalance bar arranged upon one of the side bars of the stairs, and a counterweight mounted on said counterbalanced bar.

3. In a device of the kind described, side bars provided with steps arranged therebetween, with the upper end rigidly connected

by a rigid brace member arranged in proximity to the pivotal support, a truss post rigidly secured to said rigid brace member, and a truss rod extending from the free end of said post to the inner side bar, a counterbalance bar carried by the outer side bar, and having upon its free end a counterweight arranged thereon, and means for supporting the device in operative position.

4. In a device of the kind described, side bars provided with steps arranged therebetween, with the upper end rigidly connected by a rigid brace member arranged in proximity to the pivotal support, a truss post rigidly secured to said rigid brace member, and a truss rod extending from the free end of said post to a point near the free end of the inner side bar, a counterbalance bar carried by the outer side bar, above said pivotal support, and having upon its free end a counterweight arranged thereon, a connection between said counterweight and said truss rod and means for supporting the device in operative position.

5. In a device of the kind described, a side bar provided with steps arranged therebetween, a rigid brace member rigidly connecting the side bars at their upper end, truss posts for each side bar rigidly connected to the said rigid brace member, and provided at their free ends with truss rods extending outward and connected to said bars adjacent their free ends, a counterweight bar carried by the outer side bar, and a counterweight 95 adjustably mounted upon the free end of the counterweight bar, and means for supporting the device upon the outer wall of the building.

6. In a device of the kind described, the side bars provided with steps arranged therebetween, the upper ends of the side bars being provided with depending plates rigidly secured thereto, a rigid sleeve member rigidly secured at its ends to said plate, a pivot rod loosely extending through said sleeve member, in combination with a counterweight bar carried by one side bar, a counterweight mounted on the free end of said counterweight bar, and means for supporting the device upon the outer wall of the 115 building.

7. In a device of the character described, side bars provided with steps arranged therebetween, the upper ends of said side bars being provided with depending plates rigidly secured thereto, a rigid sleeve member rigidly secured at its ends to said plate, a pivot rod loosely extending through said sleeve member, a plurality of posts extending upwardly from one of the side bars, a counterweight bar carried by said posts and positioned above said side bar, a counterweight mounted on the free end of said counterweight bar, a truss rod connecting said posts, one end of said truss rod being con- 130

nected to the outer end of the side bar and the other end of said truss rod being connected to said counterweight, and means for pivotally supporting the device.

- 5 8. In a device of the kind described, side bars provided with steps arranged therebetween, the upper ends of the side bars being provided with depending plates rigidly secured thereto, a rigid sleeve member rigidly secured to said plates and provided with upwardly extending truss posts, truss rods extending from the free ends of said posts outward from the free end of the bars and secured thereto, in combination with a coun-

terweight bar carried by one of the side bars 15 and arranged above the line of the pivot, a counterweight arranged upon the free end of the counterweight bar, and means for supporting the device upon the outer wall of the building.

20 In testimony whereof, I have hereunto signed my name in the presence of two subscribing witnesses.

FREDERICK CHARLES SEYMOUR.
